APPARATUS FOR GIVING DRAFTS TO
COTTON SLIVERS

Kikutaro Honda, Osaka, Japan

Application October 30, 1935, Serial No. 47,493
In Japan January 12, 1935

2 Claims. (Cl. 19—131)

This invention relates to improvements in an apparatus for giving drafts to cotton slivers for spinning yarns, particularly to an apparatus wherein a sliver is drafted between a pair of small endless belts passing on a pair of middle rollers of a spinning frame.

Known apparatus includes a pair of small endless belts extended on top and bottom, middle rollers, and tensers provided between front and back rollers, a sliver being drawn between the middle and the front rollers, slightly pressed by the pair of belts.

In such an apparatus, a cradle on which tensers, the top roller and the belts are mounted, is generally ridden on the bottom roller which is kept in journals on a roller-stand of a spinning frame. As a rule, six or eight bottom rollers are made in one piece, all the rollers being made of fluted portions cut out from a continuous steel bar, while two adjacent middle top rollers are made in one piece, and a spring or a weight is applied to the top rollers at the portion between the two adjacent ones in order to give a pressure to the slivers which are passing with the belts on the top and bottom rollers. In case a sliver is newly passed between the belts or the surfaces of the belts are to be cleaned, the spring or weight on the top rollers is at first slackened, and the tensers are drawn out from the cradle so that the top and bottom belts hang on the top and bottom rollers, respectively, and then the cradle is removed with the twin top rollers mounted thereon, leaving the bottom rollers placed on the roller-stand.

In this kind of apparatus, the tensers serve not only to tension the belts but also to determine a width of the clearance between the top and bottom belts at their front end. The efficiency of draft being largely dependent on this width of clearance, the top and bottom tensers are ordinarily made in one piece as an U shape, so that when it is drawn out from the cradle, both belts slack their tensions.

The pressure acting on the twin top rollers is exerted by means of a spring or a weight as before-mentioned, which is provided beneath the roller-stand through levers, and a means is also provided accompanying therewith for applying and withdrawing the pressure to and from the top rollers when it is required.

This known apparatus has several drawbacks. The construction is complicated due to existence of the pressure applying and withdrawing means for the top rollers: The endless belts are always slackened when their surfaces are to be cleaned;

Two adjacent units having top rollers, to and from which is simultaneously applied and removed the working pressure, so that an interruption of work for one unit inevitably necessitates an interruption of work of the adjacent one: The necks of the bottom roller whereon the lower edge of a cradle are supported is abraded in course of time, and the cradle is vibrated so that the sliver may be unevenly drafted. These drawbacks can be satisfactorily avoided by the present invention.

An object of this invention is to obtain an apparatus wherein a cradle is detachably fixed to a bracket and is divided into two pieces, and when these pieces are separated from each other, the top and bottom belts on the rollers and the tensers are also separated accompanying the divided pieces of the cradle, but their positions on the cradle are not changed at all so that the separated pieces of the cradle can be again set up in an operable condition without further trouble.

Another object of this invention is to obtain an apparatus wherein no pressure-applying means is required outside the cradle, and when the divided cradle is built up, an adequate pressure is simultaneously applied to the top roller by means of springs provided in the cradle.

The invention is described in detail referring to the attached drawing.

Fig. 1 is an elevation of an apparatus according to the invention. Fig. 2 is a part sectional plan view. Figs. 3 and 4 are sectional elevations on the lines III—III and IV—IV of Figs. 1 and 3, respectively. Fig. 5 is an end elevation of the apparatus when the top and bottom pieces of the cradle are being half interlocked or separated.

In the drawing, 1a and 1b are back top and bottom rollers, 2a and 2b are middle top and bottom rollers, and 3a and 3b are front top and bottom rollers, respectively. 4 and 5 are tensers for tensioning endless belts 6 and 7, which pass around the rollers 2a and 2b, respectively.

The middle top roller 2a and tensers 4 and 5 are mounted on a cradle 8, which is divided into two pieces, an upper piece 8a and a lower piece 8b.

The upper and lower pieces of the cradle have an interlocking means along their facing edges. The means may be made in various constructions, for example, recesses on one piece and spring-keys on the other piece co-operative with the recesses provided along the edge of each piece; or the co-operating edges may be made

in a dovetail section, either of the edges being slidably fitted to the other.

In the example shown in the attached drawing, the interlocking means consists of two projections 9 and 9a provided along the upper edge of each side of the bottom piece and two irregular recesses 10 and 10a provided along the lower edge of each side of the upper piece. In case the upper piece is to be interlocked with the lower one, the upper piece is at first engaged with the lower one at one of the projections 9a and recesses 10a as shown in Fig. 5, and the upper one is turned downwards until the other projection 9 is entered into the other recess 10. Then, the upper piece is slid forward a little so that both projections engage with the recesses as shown in Fig. 1.

Each side of the top piece of the cradle is provided with two inward projections 11 and 12. A spring 13 is fixed to the wall of the cradle at each side of the upper piece, and extends downwards passing through the clearance between the top side of the cradle and the projection 11, its free end being curved frontward and backward facing to the projection 12, so that a recess for holding each end of the top roller's axle is formed between them. By this means each end of the top roller's axle is yieldingly held in the position by the spring which, on the other hand, presses the axle downward co-operating with the projection 12, so that no spring or weight is required to be applied to the top roller in order to obtain an adequate pressure. In other words, as soon as the upper and lower pieces of the cradle are interlocked, the apparatus is ready for operation without requiring any further steps.

The top tenser 4 is held in a hole perforated on each side of the upper piece of the cradle, while the bottom tenser 5 is fitted to a recess provided on the upper edge of the lower piece, and is kept in its position by the lower edge of the upper piece when the latter is interlocked with the lower one as shown in Fig. 1.

The bottom piece of the cradle is detachably fixed to a bar 14 which is fixed to the roller-stand or the frame of the machine, and the lower edge of the cradle does not touch the surface of the bottom roller.

The bar 14 is provided with a spring 15 for each cradle, and another spring 15a provided at the lower end of the bar is bent upward to make a space for receiving the lower end of the piece 8b. A key 16 is fixed at the upper part of the spring, which fits to a hole 17 perforated in the back wall of the lower piece. When the lower piece is pushed down over the bottom roller 2b,

the back wall is firmly fixed to the bar 14 by means of the spring 15a and the key 16.

While the top roller is made separately for each unit, six or eight bottom rollers are made on one piece as usual. The lower belt 7 passes over the bottom roller, and its front end is stretched by the bottom tenser 5, while the upper belt 6 is also extended between the top roller and the top tenser 4, and a cotton sliver 18 passes the clearance between the two belts. Each unit can be stopped independently of the other unit.

In case the surface of the belts are to be cleaned or a new sliver is to be inserted between the belts, the upper piece of the cradle is disengaged from the bottom one in the reversed way to that for interlocking before mentioned. Both endless belts are now exposed, but each of them is still extended over its roller and tenser mounted on the upper and lower pieces of the cradle, respectively.

The top roller can be easily removed from the top piece of the cradle, if desired, by forcibly pulling out the roller so that the free end of the spring 13 is forced to pass the axle of the roller.

What I claim is:—

1. An apparatus for giving draft to a cotton sliver for spinning yarns comprising a cradle divided into upper and lower pieces and provided with an interlocking means of the pieces, an independent top roller yieldingly held in the upper piece, a spring provided in the upper piece in order to press the top roller downwards, a means provided on the lower piece of the cradle so as to detachably fix the piece to the frame of the machine, and a lower tenser inserted in a recess provided on each side of the upper edge of the lower piece of the cradle, firmly held in its position by the lower edge of the upper piece of the cradle when the upper piece is interlocked with the lower one.

2. An apparatus for giving draft to a cotton sliver for spinning yarns comprising a cradle divided into upper and lower pieces and provided with an interlocking means of the pieces, a means provided on the lower piece of the cradle so as to detachably fix the piece to the frame of the machine, an independent top roller yieldingly held in the upper piece, a spring fixed to each side of the upper piece of the cradle to press the top roller downwards with its free end bent in such a manner as to yieldingly hold the axle ends of the independent roller, said cradle being constructed and arranged to form one of a series of cradles serving a common bottom roller.
